LUBRICATING PUMP

Franz Urschler, Vienna, Germany, assignor to the
firm Alex. Friedmann, Vienna, GermanyApplication February 25, 1939, Serial No. 258,395
In Austria January 8, 1938

1 Claim. (Cl. 184—27)

The object of the present invention is to provide a simple piston lubricating pump capable of operating continually also against very high counter-pressure and permitting the delivery of 5 each individual pumping unit to be regulated at will. With these and other purposes in view the improved piston lubricating pump is designed as follows:

The lubricating pump comprises single-piston pumping units having pistons or plungers actuated by rectilinearly guided slides and so arranged 10 relatively to the shaft carrying the operating eccentric that their axes approximately intersect the axis of said shaft whereby it is obtained that only few members are subject to wear and detrimental bending strains of the pistons are obviated. In spite of the fact that with this arrangement no free space is left above the heads of the pistons, the possibility of regulating the stroke of every piston in a simple manner is simultaneously 15 obtained by the provision of an adjustable abutment on the part of the slide located between said shaft and the respective piston head and transmitting the power from the respective eccentric to said piston head, said abutment permitting to vary the size of the jaw of said slide 20 embracing the piston head. By these simple means it is possible to design a lubricating pump fitting with adjustable single-piston pumping 25 units and capable of operating continually against very high counter-pressure.

For adjusting the above-mentioned abutment in the jaw of the slide embracing a piston head, cooperating adjusting members may according to 30 the invention be provided on said slide and connected with an adjusting device arranged on the pump casing, said adjusting device being accessible from the outside and indicating the adjustment.

Furthermore, the suction port of each pumping 35 element may be located at the highest point of the operating chamber of the piston so that the latter passes over the said suction port and closes it during its pressure stroke and a drip chamber 40 with a transparent wall may be inserted in the suction passage of each pumping unit so that the amount of lubricant drawn in by the pumping unit from the oil container is made visible in the form of drops. With this arrangement any lubricant passing through the clearance between the piston and the bore of the cylinder during the pressure stroke can only get into the suction passage. It will partly destroy the vacuum created 45 within the drip chamber by the preceding suction stroke and during the following suction

stroke only the amount of oil actually delivered to the point of lubrication during one pressure stroke will be drawn in through the drip chamber in the form of freely falling drops.

The invention is diagrammatically illustrated 5 by way of example in the accompanying drawing in which Fig. 1 is a vertical cross-section of a piston lubricating pump according to this invention, and Fig. 2 is a vertical longitudinal section thereof.

In the drawing, 1 denotes the pump casing forming the oil receptacle, arranged within said casing 1 are the single-piston pumping units each comprising a cylinder 2 and a piston 3 fitted into the bore 4 of the cylinder. 5 denotes the suction port which is covered and closed by the piston 3 during its pressure stroke while said piston forces the lubricant through a check valve 6 into the passage 7 and thence to the point of lubrication. The head 8 of the piston 3 is embraced by the 10 prongs of the forked end of the jaw or claw 9 of a slide or yoke member 10 reciprocated along a bolt 11 parallel to the axis of the piston 3 by means of an eccentric provided on the main shaft 13. 15

As shown in Fig. 2 the shaft 13 carries a plurality of eccentrics 12 staggered relatively to one another, each eccentric actuating a slide 10 and a pumping unit 2, 3. The axis of each piston 3 is so arranged that its extension perpendicularly 20 intersects the axis of the shaft 13. By these means any detrimental bending strain on the piston 3 during operation is obviated. For transmitting the power from the eccentric to the slide during the pressure stroke a sliding block 14 is 25 inserted between each eccentric and the slide cooperating therewith.

In the jaw 9 of the slide 10 and more particularly on the portion 16 of the slide situated between the eccentric 12 and the piston head 8, an adjustable abutment 15 is rotatably mounted on a bolt 17. The said abutment 15 consists of a disc having a helical lower surface and permitting to fill the intermediate space between the piston head 8 and the upper surface of the jaw 9 to a greater or lesser extent according as the said disc is turned around the bolt 17. 40

To enable the said disc to be turned, it is provided with a toothed rim 18 engaging a second adjusting member, namely the gear wheel 19, 50 the shaft 20 of which is supported by the portion 16 of the slide. The shaft 20 receives in its bore 21 the coupling bolt 23 which is rotatably supported on the casing 1. A pin 24 passing through the shaft 20 is free to glide in the longi- 55

tudinal slot of the coupling bolt 23 when the slide moves up and down. The coupling bolt 23, which carries on its upper part an adjusting knob 26 provided with a projection 31, is supported in 5 the index disc 28. These members constitute together an adjusting device for the adjusting members 18, 19 and the abutment 15. The projection 31 indicates on the index disc 28 the position of the abutment 15 and, therefore, the 10 delivery for which the respective pumping unit 2, 3 is adjusted. If the adjusting knob 26 is turned, also the helical disc 15 will be turned to a corresponding extent and the travel of the piston will be correspondingly increased or diminished. 15

It appears from the preceding description that in spite of the piston 3 being so arranged that its axis perpendicularly intersects the axis of the shaft 13 carrying the excentrics it is possible to provide an adjusting device accessible from the outside for regulating the stroke of the piston 3 and indicating the adjustment on an exterior scale, and to transmit the power from the shaft 13 by means of the slide 10 to the piston head 8 without subjecting the piston 3 to any detrimental strain of flexure. 20

In order to enable the amount of lubricant drawn in by the piston 3 from the oil container 1 at every piston play to be observed, the suction port 5 of the cylinder 2 communicates with the two passages 27, 32 in which a drip or sight chamber 22 is inserted. As soon as the piston 3 uncovers the suction port 5 on its intake stroke the lubricating oil is drawn from the oil reservoir 30 35 through the pipe 32 and the nozzle 29 into the drip chamber and thence through the passage 27 and the suction port 5 into the operating chamber 4 of the cylinder 2. The walls of the drip

chamber 22 are formed by a glass tube 30 so that the oil dripping from the nozzle 29 may be seen from the outside. Any oil leaking through the clearance between the piston 3 and its bore 4 of the cylinder during the discharge stroke can only pass into the suction passage 27 from where it is invariably drawn back again at the beginning of the next intake stroke. As the piston 3 continues its upward movement, new oil will be drawn in from the oil reservoir through the 10 nozzle 29 in a quantity corresponding to that which is actually delivered to the point of lubrication during the discharge stroke. 15

What I claim is:

In a high pressure reciprocating lubricating 15 pump, a casing, a cam shaft within said casing, a rectilinearly guided yoke member engaged by and being reciprocatingly operated by said cam shaft, said yoke member having a claw portion extending therefrom and having a forked end, 20 an adjusting member revolvably connected with said yoke member and extending into said claw portion, a pump piston extending in between the prongs of said forked end and having a head 25 extending into said claw portion and being held thereby and abuttingly cooperating with said adjusting member, the longitudinal axis of said piston intersecting with the axis of said cam shaft, the axis of rotation of said adjusting member being spaced from and parallel to the axis of 30 said piston, adjusting member operating means extending outside of said casing and operatively engaging and being adapted to rotate said adjusting member, said adjusting member having circumferential portions of different thicknesses 35 and, upon rotation, affording change of position of said piston relatively to said yoke member.

FRANZ URSCHLER.
